UNITED STATES PATENT OFFICE.

FERMAN A. SMITH, OF COLEMAN, TEXAS.

COTTON PRESS.

Application filed November 22, 1924. Serial No. 751,675.

To all whom it may concern:

Be it known that I, FERMAN A. SMITH, a citizen of the United States, residing at Coleman, in the county of Coleman and 5 State of Texas, have invented certain new and useful Improvements in Cotton Presses, of which the following is a specification, reference being had to the accompanying drawings.

10 This invention relates to certain improvements in cotton presses and it is an object of the invention to provide a device of this general character wherein means are provided for lifting the doors of the press.

15 Another object of the invention is to provide a press consisting of double bale boxes arranged to swing upon a center post the upper portion of each of the boxes being provided with swinging doors together with 20 means for lifting said doors so that the requisite swinging of the bale boxes from one position to the other may be obtained without hindrance or obstruction being offered by the doors.

25 The invention consists in the details of construction and in the combination and arrangement of the several parts of my improved cotton press whereby certain important advantages are attained and the device 30 rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:—

40 Figure 1 is an elevational view illustrating the press having a door closing attachment applied thereto in accordance with an embodiment of my invention;

Figure 2 is a sectional view taken substantially on the line 2—2 of Figure 1.

As disclosed in the accompanying drawings, 1 denotes a center post interposed between a top beam 2 and a bottom beam or sill 3, said beams 2 and 3 being comprised 50 in the stationary frame work of the press.

Supported by the center post, as at 4, for swinging movement therearound are the bale or press boxes B, the lower portion of each of which being preferably made solid while 55 the upper part is provided with the side doors 5 of a desired construction and which

are adapted to be swung outward and downward to free a bale to permit its removal.

It is now the general practice to return the swinging doors to their raised or closed position by weighted members operatively engaged therewith by suitably disposed cables which are hooked or otherwise attached to the doors before the bales are swung about the center post to change their positions. It 60 frequently occurs that the pressman fails to properly hook the cables to the doors so that upon turning the bales the doors interfere with the requisite swinging movement of the boxes, necessitating the boxes being returned to the position whereby said flexible members may be hooked thereto. This 65 materially interferes with the baling operation and particularly to reduce the output.

As herein disclosed, I provide a novel and improved attachment for each of the doors 5 which comprises a pulley 6 supported for rotary movement by a trunnion or stub shaft 7 carried by a top girder 8 comprised in the top part of the lower portion of the 70 box B. Secured to the peripheral portion of the pulley 6 is a flexible member 9, herein disclosed as a chain, said member or chain 9 extending downwardly and having its lower end portion fixed to an extremity of a coil spring 10. The opposite end portion of the 75 spring 10 is anchored, as at 11, to a bracket 12 affixed to a bottom girder 14 of the lower portion of the box B.

Extending outwardly and substantially 80 radial from the pulley 6 is an elongated arm 15 the outer end portion 16 of which being disposed on an inward incline so that the outer or free extremity of the arm 15 will overlap a side portion of the door 5. This 85 free extremity of the arm 15 carries a roller 17 which has direct contact with the door 5. When a door 5 is swung outwardly and downwardly to free a bale compressed within the upper portion of the box B the adjacent arm 15 will also be forced downwardly resulting in the flexible member or chain 9 being wound upon the pulley 6 and placing the spring 10 under tension and just 90 as soon as the bale has been properly freed or released, the tension of the spring 10 will be sufficient to swing the arm 15 upwardly and return the door 5 to its closed position. By this means it will be noted 95 that the door 5 is automatically raised or returned to its closed position and thus obviating the delay which would otherwise 100 105 110

occur in the event the pressman should overlook raising or lifting such door in the manner now generally in use.

From the foregoing description it is thought to be obvious that a cotton press constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In a cotton press, the combination of a press box having a swinging side door, an arm supported by the box for swinging movement and having contact with the door, and a spring engaged with the arm and placed under tension when the door is moved into open position to cause said spring and arm to automatically swing the door in the opposite direction.

2. In a cotton press, the combination of a

press box having a hinged side door, a pulley rotatably supported by the box, an outstanding arm carried by the pulley, the free extremity of the arm overlapping the swinging door, a flexible member attached to the pulley, and a spring attached to the flexible member and to the box, the door when moved into open position swinging the arm and pulley to place the spring under tension to cause said spring to automatically move the door in the opposite direction.

3. In a cotton press, the combination of a press box having a hinged side door, a pulley rotatably supported by the box, an outstanding arm carried by the pulley, the free extremity of the arm overlapping the swinging door, a flexible member attached to the pulley, a spring attached to the flexible member and to the box, the door when moved into open position swinging the arm and pulley to place the spring under tension to cause said spring to automatically move the door in the opposite direction, and a roller carried by the free extremity of the arm for direct contact with the door.

In testimony whereof I hereunto affix my signature.

FERMAN A. SMITH,
